ABSTRACT: The control coils of fuel injection valves, one coil to one valve, are electrically connected to form a plurality of coil groups. During the low-speed operation of the engine, said groups of coils are sequentially energized so that the valves alternate in their injection action. When the sum of the coil energizing duration and a certain predetermined duration exceeds the duration proportional to the time required by engine to complete one revolution as the speed of the engine rises, the groups of the control coils and thus the fuel injection valve are switched so as to be energized simultaneously.

ELECTROMAGNETIC FUEL INJECTION SYSTEM FOR INTERNAL-COMBUSTION ENGINES

This invention relates to the electromagnetic fuel injection system and, in particular, to an electromagnetic fuel injection system for internal combustion engines of the type in which fuel injection is effected selectively for engine cylinders by switching between one number of cylinders and another number in ratio of 1 to 2.

In conventional electromagnetic fuel injection systems, fuel injection quantity is controlled by means of the energizing duration T in which voltage is applied to electromagnetic or solenoid type injection valves. As the engine r.p.m. N rises, the control duration t ($=60/N$ second), i.e., the duration in which fuel injection quantity can be controlled, shortens and may become shorter than the energizing duration T to result in temporary loss of control.

According to the conventional system, fuel injection is effected simultaneously into the intake pipes of all of the cylinders in the four-stroke cycle engine, so that it could occur that, in some cylinders at a certain time during operation, the intake and the exhaust valve are both open, presenting a condition of so-called "valve overlap" to allow the fuel-air mixture to partially escape direct into the exhaust line. Such escape is particularly wasteful during low-speed engine operation and increases the overall fuel consumption of the engine.

In order to overcome the shortcomings of the conventional system noted in the above, we proposed, by our Japanese Patent application 47098/68, to divide the engine cylinders into two or more groups; to reduce the number of cylinders simultaneously receiving fuel in low-speed engine operation, that is, when the control duration t is relatively large, in such a way as to minimize or avoid the concurrence of injection timing with said "valve overlap" in the respective cylinders; and to increase the number of simultaneously fuel-receiving cylinders, when the engine is running fast, in order to prolong, in an equivalent and relative sense, the control duration t , which is then relatively short.

In the method proposed, the change of the number of simultaneously energized injection valves is to be effected at a predetermined level of engine speed by means of a switch operating in response to engine speed. Then, even a short energizing duration T , meaning a small injection quantity, can be adequately varied for control purpose even if the engine is running fast as long as there is a sufficient time margin or leeway due to the difference between a short duration T and a long duration t . But when the duration T is made very long, the temporary loss of control might result even when the engine is running slowly. In other words, the method of switching from one number of simultaneously fuel-receiving cylinders to the other at a predetermined r.p.m. level does not reckon with the controllability of energizing duration T at all speeds of the engine.

The object of the present invention is to provide an improvement over the method previously proposed by this inventor, and contemplates addition of some predetermined length of duration to the energizing duration T and effecting said switching just when the sum of these two durations increases to exceed the duration, of which mention will be made later, proportional to the time required by engine crankshaft to complete one revolution, so that said switching will not entail such temporary loss of control as was stated in the above. Said additional duration is to be determined on the basis of desired time range within which the duration T for injection fuel can be varied.

Stated briefly, the electromagnetic fuel injection system according to the present invention comprises a means of closing a circuit at the moment the sum of the energizing duration proportional to the time required by engine crankshaft to complete one revolution, and also pulse shunting circuits for bypassing and thereby making ineffective the pulse trains by which the solenoids or coils of said injection valves are otherwise caused to operate for fuel injection, so that all of the injection valve solenoids will be energized simultaneously when

and if said sum exceeds the duration for one crankshaft revolution.

For the switching means, this inventor prefers to use a thyristor and two transistors so adapted and combined that one of the two transistors changes to positive the polarity of voltage applying across said thyristor, from its anode to cathode, immediately and instantly after said duration for one crankshaft revolution lapses, while the other transistors applies positive voltage to the thyristor gate during that portion of said predetermined duration following the energizing duration T . As the two transistors so operate, the thyristor becomes ready to conduct when said sum of the two durations increases to match, or become equal to, the duration for one crankshaft revolution.

15 The pulse shunting circuits should preferably contain diodes for blocking the shunting paths there with to defeat said shunting action. These diodes are to become conductive to shunt the the pulse trains when said switching means starts conducting.

20 Moreover, the system according to the invention preferably includes a circuit which reduces, when said switching means becomes conductive, the frequency of the pulse in said trains, each pulse being the determinant of the length of energizing duration T . This circuit is to halve the frequency of fuel injection concurrent with a switching from alternate two-cylinder injection to four-cylinder injection in a four-cylinder engine, for example, and thus equalizes injection quantities prior and subsequent to the switching.

25 30 The invention will be further explained, and other features will become apparent, from the following description, with reference to the accompanying drawings, in which:

FIG. 1 is the circuit diagram of a system according to the invention, and FIG. 2 is a line diagram for illustrating the operations of the system.

35 Referring now to FIG. 1, section A is a converter of known type for translating the revolving speed of the engine into a pulse voltage; section B is a monostable multivibrator of known type, generating square-wave pulses whose signal frequency is proportional to the speed of the engine and whose signal width varies with the vacuum in the engine intake line; section D is an output amplifier for controlling the energization of the fuel injection valves on the engine; section C is a selector for selecting the number of injection valves by 40 45 switching for simultaneous injection; and block E is a smoothing circuit of any known type.

40 45 Section A comprises switches S_1 , S_2 , which are actuated from the cam in the breaker of the engine; condensers C_1 , C_2 ; and resistors r_1 through r_6 , inclusive. Resistor r_1 has its one end connected to conductor W_1 , leading from the positive side of the power source, not shown, and other end to the movable contact of switch S_1 , whose stationary contact is connected to conductor W_2 leading from the negative side of said power source. Similarly, resistor r_2 has its one end connected to conductor W_1 and other end to the movable contact of switch S_2 , whose stationary contact is connected to conductor W_2 . Between conductors W_1 and W_2 are located dividers composed of resistors r_3 , r_4 and resistors r_5 , r_6 . Connection point J_1 is between resistors r_3 and r_4 ; another connection point J_2 is between resistors r_5 and r_6 . Condenser C_1 is connected between said point J_1 and switch S_1 , and condenser C_2 between point J_2 and a circuit in sections C and D.

50 55 The monostable multivibrator, or section B, comprises such timing elements as transistors Tr_1 , Tr_2 , transformer L, and resistors R_0 , R_1 . The emitters of these transistors are connected direct to conductor W_2 . The collector of transistor Tr_1 is connected to W_1 through resistor r_7 and to W_2 through resistors r_8 , r_9 . A branch circuit formed of series-connected resistor R_1 , 3, D_6 and resistor R_2 is connected between W_1 and W_2 . The base of transistor Tr_1 is connected to the connection point between said resistor R_2 and diode D_6 . Transistor Tr_2 has its emitter connected direct to W_2 , base to the connection point between r_8 and r_9 , and collector to W_1 through the primary winding L_1 of transformer L and resistors r_{10} . A divider circuit, consisting

of resistors $R_3 R_0$, is formed between conductors W_1 and W_2 . The secondary winding L_2 has its one end connected to the connection point between R_3 and R_0 and other end connected, through diode D_3 , to the connection point W between resistor R_1 and diode D_6 . The core, not shown, of transformer L is so adapted as to be displaced in position by diaphragm D_1 , which moves in response to changes in negative pressure or vacuum in the engine intake pipe P . By this displacement of the core, the inductance of transformer L is varied in response to changes in vacuum. The connection point W is connected to said points J_1 and J_2 through a respective diode, D_1 for J_1 and D_2 for J_2 .

Section D comprises two sets of transistors, Tr_8 and Tr_9 for one set and Tr_{10} and Tr_{11} for the other set, with which are associated, in two sets, resistors r_{10} through r_{21} , inclusive, and control coils, L_1 through L_4 , inclusive, for the solenoid type fuel injection valves. Transistor Tr_8 has its emitter connected direct to conductor W_2 ; collector is connected, through resistor r_{13} , to conductor W_1 and, through resistors r_{14} and r_{15} , to conductor W_2 ; and base is connected, through resistors r_{10} , r_{11} and conductor l_1 , to the movable contact of switch S_1 and, through resistor r_{12} , to the terminal U_1 leading to the collector of transistor Tr_2 . Transistor Tr_9 has its emitter connected to conductor W_2 ; base is connected to the connection point between resistors r_{14} and r_{15} ; and collector is connected to one end of the parallel control coils L_1 , L_2 . The other end of these parallel coils is connected direct to conductor W_1 . The other half of section D, comprising transistors Tr_{10} , Tr_{11} , is formed in the same way as the half thus far described, the difference being that the one end of resistor r_{16} is connected, through conductor l_2 , to the movable contact of switch S_2 .

Section C comprises control resistors Tr_{12} , Tr_{13} and switching-action thyristor SCR for controlling the selection of the number of injection valves for simultaneous injection. Thyristor SCR has its cathode connected direct to conductor W_2 and anode to conductor W_1 through resistor R_{12} . Transistor Tr_{12} is connected across thyristor SCR, with its emitter tied to the cathode side and collector to the anode side. The base of this transistor is connected to the connection point between resistors R_{10} and R_{11} . The outer end of R_{10} is connected to conductor W_2 , and the outer end of R_{11} to the conductor l_2 . Transistor Tr_{13} has its emitter connected direct to conductor W_2 , and collector to the connection point U_{12} between R_{14} and R_{15} . Resistors R_{14} , R_{15} , together with resistors R_{13} , constitute a divider as located between W_1 and W_2 . Into the connection point between R_{13} and R_{14} is tied the gate of thyristor SCR. The base of transistor Tr_{13} is connected to the point between resistor R_{17} and the cathode of diode D_{10} , the outer end of resistor R_{17} being connected to W_2 and the anode end of diode D_{10} being connected, through resistor R_{16} , to conductor W_1 and, through condenser C_{10} and resistor R_{18} , to the collector of transistor Tr_8 . The anode of thyristor SCR is connected to smoothing circuit E , which leads through two separate paths to the connection point between resistor r_{16} and r_{17} through diode D_5 and to the point between resistors r_{10} and r_{11} through diode D_4 .

Having thus far described the circuit arrangement of the system, the operations of the circuit components for accomplishing the objects of the invention will be explained in reference to FIGS. 1 and 2, first by assuming the switching-action thyristor SCR to be in nonconductive state. It should be noted that the cathode side of diodes D_4 , D_5 is kept at positive potential by the smoothing circuit E , so that positive voltages due to the opening of switches S_1 , S_2 will not apply to the thyristor SCR side through these diodes to interfere with the normal operation of transistors Tr_8 , Tr_{11} .

Switches S_1 , S_2 in the r.p.m.-voltage conversion circuit open and close alternately when the engine is running. Suppose switch S_1 has just closed: by this closure, negative voltage applies from conductor W_2 to the base of transistor Tr_8 through resistors r_{10} , r_{11} and conductor l_1 and, at the same time, condenser C_1 discharges. The discharge current of condenser C_1 , which has been charged from positive-potential W_1 , flows

through switch S_1 and resistor r_3 , causing the potential of connection point J_1 to turn negative. The negative potential of J_1 enables diode D_1 to conduct, thereby generating a trigger pulse, and changes the potential of connection point W to negative. By this negative potential, diode D_6 becomes held in blocking state to apply negative voltage to the base of transistor Tr_1 . Consequently, transistor Tr_1 becomes nonconductive and, under this condition, a positive voltage determined by the ohmic sizes of divider resistors r_7 , r_8 , r_9 applies to the base of transistor Tr_2 . As transistor Tr_2 conducts, current flows in the primary coil L_1 of transformer L to induce voltage in secondary coil L_2 . By this induction, current flows through resistors R_0 , R_1 , diode D_3 and coil L_2 to increase the voltage drop across resistor R_1 and thus makes the base of transistor Tr_1 more negative. These events constitute a positive feedback.

The current due to the induced voltage, which decreases exponentially, holds the base of Tr_1 negative and maintains transistor Tr_2 in conductive state until the current falls exponentially to and below a predetermined value. It will be noted that the primary current inducing a secondary current is a function of the time constant of the primary-side reactance and resistance. Since the reactance varies with the position of the transformer core, and because the core displaces itself in response to a change in the engine intake pipe vacuum, the width of the pulse T_0 occurring at the connection point U_1 varies with said vacuum.

Because the bases of transistors Tr_8 , Tr_{11} are connected to point U_1 , the pulse T_0 gives a negative potential to these bases for the duration of the pulse. Because switch S_2 is open at this juncture, the base of transistor Tr_{11} has been kept to positive potential. During the period of T_0 , therefore, two negative pulses are applying to the base of Tr_8 to make this transistor nonconductive, while the base of Tr_{11} is receiving the negative pulse and a positive pulse due to switch S_2 in open position. The net result of the negative and the positive pulse at the base of Tr_{11} is positive, because of the divider circuit, so that this transistor conducts. Thus, the nonconducting Tr_8 causes transistor Tr_9 to conduct and the conducting Tr_{11} causes Tr_{10} to stay nonconductive. With the current so conducted by Tr_9 , coils L_1 , L_2 become energized to effect fuel injection by their valves.

As switch S_1 opens, switch S_2 closes. By the opening of switch S_1 , a positive voltage applies through resistor r_1 , conductor l_1 , resistors r_{10} , r_{11} to the base of transistor Tr_8 , and by the closure of switch S_2 , negative voltage applies through switch S_2 , conductor l_2 , resistors r_{16} , r_{17} to the base of transistor Tr_{11} . At the same time, the condenser C_2 , which has been charged from the positive conductor W_1 through resistor r_2 , conductor l_2 , resistor r_{16} and conductor l_3 , discharges. The discharge current flows through resistor r_5 , condenser C_2 , conductor l_3 , resistor r_{16} and switch S_2 to turn to negative the potential of connection point J_2 . As a result, a trigger pulse, inducted by conduction through diode D_2 , applies to connection point W , just as in the case of the closure of switch S_1 considered previously. This pulse gives rise to a negative pulse T_0 at point U_1 , which applies to the base of transistors Tr_8 , Tr_{11} to make Tr_8 conductive and Tr_{11} nonconductive, so that, while Tr_8 becomes nonconductive, Tr_{10} becomes conductive to energize coils L_2 , L_4 for effecting fuel injection by their valves. In the present instance, it should be recalled that coils L_1 , L_2 and coils L_3 , L_4 are in two respective sets, and each set of coils with their injection valves are energized simultaneously to perform simultaneous fuel injection. These sets alternate in the sequence of fuel injection. This manner of injection will hereafter be referred to, for brevity, as two-cylinder injection.

Next, the operation of the system with thyristor SCR in conductive state will be explained. As switch S_2 closes and opens, a square-wave pulse having its width corresponding to the duration of closure applies to the base of transistor Tr_{12} through its base resistor R_{12} to keep this transistor in off state. The resultant voltage across the emitter and collector is indicated

as voltage U_{10} , FIG. 2, and identical to the square-wave pulse whose duration is T_{10} . By this voltage, the anode of thyristor SCR becomes positive in polarity with respect to its cathode.

Now, the potential of terminal M illustrated at U_{11} in FIG. 2 is that of the collector transistor Tr_8 , and changes according as solenoids L_1, L_2 are energized or not. When the potential M becomes positive, current flows into condenser C_{10} through resistor R_{18} to charge the condenser. This charging is quick because resistor R_{18} is sized small in ohmic value, and takes place through the path including said R_{18}, C_{10} , diode D_{10} , base and emitter of transistor Tr_{13} . As the potential of terminal M becomes negative, condenser C_{10} discharges through the path including R_{18}, C_{10} and R_{18} . While this discharging current is flowing, the base of transistor Tr_{13} stays negative with respect to the emitter and keeps this transistor in off state. The duration of the off state is determined by the time constant of the discharge circuit, that is, mainly of C_{10} and R_{18} ; and the duration of the pulse voltage arising from this off state of transistor Tr_{13} across its collector and emitter is due to said time constant and corresponds to duration T_{12} of voltage U_{12} . As will be noted in FIG. 2, square-wave pulse U_{12} immediately follows pulse U_{11} . If the sum duration of T_{12} and T_{11} exceeds the duration T_{10} which is the duration proportional to the time required for one revolution of engine crankshaft, as stated at the onset, thyristor SCR will conduct, because thyristor gate is at a positive voltage determined by the ohmic value of divider resistors R_{13}, R_{14} while a positive voltage is across the thyristor anode and cathode due to switch S_2 being in closed state at this time. A thyristor SCR so conducting signifies that control of injection quantity by alternate two-cylinder injection is temporarily lost. To circumvent this condition, the number of simultaneously injecting valves must be increased and, at the same time, the frequency of injection must be reduced in proportion to the increase in the number of valves so that the said excess will disappear to revive control of injection quantity, that is, to make the control duration t effective. These requirements are met in the present invention in the following manner.

With thyristor SCR conducting as above, the trains of pulses arriving from switches S_1, S_2 at the bases of transistors Tr_8, Tr_{11} for energizing the solenoids flow through diodes D_4, D_5 and thyristor SCR into the negative conductor W_2 and, as a result, the bases of these transistors remain at negative potential to cause transistors Tr_8 and Tr_{11} to conduct simultaneously, thereby energizing both sets of solenoids L_1, L_2 and L_3, L_4 . In the illustrated instance, the circuit from diodes D_4, D_5 to thyristor SCR shunts the bases of transistor Tr_8, Tr_{11} to the thyristor and, by so shunting, switches from alternate two-cylinder injection to simultaneous four-cylinder injection.

Note that one end of condenser C_2 is connected to the base of transistor Tr_{11} , so that the train of pulses arriving from switch S_2 is shunted to the negative conductor W_2 when the thyristor is in conductive state. This means that one of the two trigger pulses generated by the monostable multivibrator is eliminated to halve the trigger pulse frequency and thus double the interval between two successive pulses. The net effect of the doubled interval is obviously the unchanged fuel injection quantity through the transition from alternate two-cylinder injection to simultaneous four-cylinder injection.

Although alternate two-cylinder injection and simultaneous four-cylinder injection are considered in the above description of the system illustrated in the drawing, it will be readily seen from the spirit of the invention that the present invention can be applied to the switching between three cylinders and six cylinders, even between one cylinder and two cylinders in a four cylinder engine, or between any two numbers of cylinders as long as the ratio of the numbers is 1 to 2.

We claim:

1. An electromagnetic fuel injection system for internal combustion engines, having a plurality of injection valve control coils electrically connected to form a plurality of independent coil groups which are alternately energized during the low-speed operation and simultaneously energized during the

high-speed operation of the engine, comprising: a switching means which becomes conductive when the sum of the duration for energizing said control coils and a predetermined duration corresponding to the injection quantity control range exceeds the duration proportional to the time required by engine crankshaft to complete one revolution, and a pulse shunting circuit which, when said switching means becomes conductive, shunts the pulse trains used to alternately energize the said groups of coils, so that said control coil groups become energized simultaneously.

2. A system according to claim 1, in which the switching means is composed of a thyristor and two transistors, one of said transistors being adapted to turn to positive the polarity of the voltage impressed across the anode and cathode of said thyristor upon termination of the duration proportional to the time required by engine crankshaft to complete one revolution, and the other transistor being adapted to apply a positive voltage to the gate of said thyristor during the predetermined duration corresponding the injection quantity control range upon termination of the duration for applying energizing voltage to said control coils.

3. A system according to claim 1, in which the pulse shunting circuit includes diodes shunting the trains of pulses used to alternately energize said control coil groups through said switching means.

4. An electromagnetic fuel injection system for an internal combustion engine, having a plurality of injection valve control coils electrically connected to form a plurality of independent coil groups which are alternately energized during the low-speed operation and simultaneously energized during the high-speed operation of the engine, comprising: a first transistor connecting said control coil groups respectively to the source of voltage; a second transistor for controlling said first transistor, to which are applied as input signals, a first pulse voltage having a pulse frequency proportional to engine running speed and a pulse width varying with the vacuum in the engine intake pipe and a second pulse voltage for alternately energizing said control coil groups; a switching means which becomes conductive at the moment the sum of the duration for energizing said control coils and a predetermined duration corresponding to the injection quantity control range exceeds the duration proportional to the time required by engine crankshaft to complete one revolution; and a pulse shunting circuit which, when said switching means becomes conductive, shunts the pulse trains used to alternately energize the said groups of coils, so that said control coil groups become energized simultaneously.

5. A system according to claim 4, in which the switching means is composed of a thyristor and two transistors, one of said transistors being adapted to turn to positive the polarity of the voltage impressed across the anode and cathode of said thyristor upon termination of the duration proportional to the time required by engine crankshaft to complete one revolution, and the other transistor being controlled with the output of said second transistor through a time constant circuit comprising a capacitor and resistor and adapted to apply, upon termination of the duration for applying voltage to and thereby energizing said control coils, a positive voltage to the gate of said thyristor during the predetermined duration corresponding to the injection quantity control range.

6. A system according to claim 4, in which the pulse shunting circuit includes diodes shunting said second pulse voltage through said thyristor.

7. An electromagnetic fuel injection system for internal combustion engines, having a plurality of injection valve control coils electrically connected to form a plurality of independent coil groups which are alternately energized during the low-speed operation and simultaneously energized during the high-speed operation of the engine, comprising: a switching means which becomes conductive when the sum of the duration for energizing said control coils and a predetermined duration corresponding the injection quantity control range exceeds the duration proportional to the time required by engine

crankshaft to complete one revolution; a pulse shunting circuit which, when said switching means becomes conductive, shunts the pulse trains used to alternately energize said groups of coils, so that said control coil groups become energized

simultaneously; and a circuit which reduces, when said switching means conducts, the frequency of the pulse voltage determining the duration for applying energizing voltage to said control coils.
